CLAIM

(52) **U.S. Cl.** **D14/136**

The ornamental design for a combined disc player and
amplifier, as shown and described.

(58) **Field of Classification Search** D14/135–136,

DESCRIPTION

D14/156–157, 160–165, 167–168, 193–198,
D14/188, 217, 257, 258, 445; 360/99.02,

FIG. 1 is a perspective view of a combined disc player and
amplifier showing my new design;

360/99.07; 720/612, 619, 647, 655; 455/344,

FIG. 2 is a front elevational view thereof; and

455/347–351; 369/77.11, 75.11, 75.21, 77.21

FIG. 3 is a left side elevational view thereof;

See application file for complete search history.

FIG. 4 is a right side elevational view thereof;

(56) **References Cited**

FIG. 5 is a top plan view thereof; and,

FIG. 6 is a bottom plan view thereof.

Portions of FIGS. 1–6 that are shown as broken lines are for

illustrative purpose only and form no part of the claimed
design.
